UNITED STATES PATENT OFFICE

CESARE BARBIERI, OF NEW YORK, N. Y., ASSIGNOR, BY MESNE ASSIGNMENTS, TO
VORTEX CUP COMPANY, OF CHICAGO, ILLINOIS, A CORPORATION OF DELAWARE

CONICAL CUP DISPENSER

Application filed October 31, 1928. Serial No. 316,282.

This invention pertains to a cup dispenser, and more particularly to a dispenser adapted to permit conical cups to be dispensed one at a time from a magazine through a base member equipped with groups of cup retaining members, with the members of one group positioned exactly above the members of another group to afford an arrangement whereby the withdrawal of more than one cup at a time is obviated due to the fact that the second group of members serves as a means for holding back additional cups which accidentally may pass the first group of retaining members.

It is an object of this invention to provide a cup dispenser adapted to be mounted in a vertical position on a wall or similar support and having a base member constructed in the form of a band having layers of radially directed retaining members integrally formed thereon to partially restrict the passage of cups through the base to insure individual dispensing of the cups.

It is also an object of this invention to provide a conical cup dispenser having a plurality of parallel layers of radially directed teeth formed therein with the teeth of one layer disposed exactly above the teeth of another layer to afford a partial restriction to the passage of cups through the dispenser permitting the cups to be withdrawn in consecutive order past the radially directed teeth which act to deflect portions of the margins of the cups inwardly thereby temporarily scalloping the margins of the cups to insure discharge of only one cup at a time from the dispenser.

It is a further object of this invention to provide a conical cup dispenser having a base provided with groups of retaining members disposed in substantially parallel planes, said base having supported therein a cup magazine or container provided with latching members adapted to be moved into engagement with certain of the retaining members within the base to hold the magazine removably locked in position with respect to the base.

It is furthermore an object of this invention to provide a cup dispenser wherein a base is provided with parallel and aligned groups

of retaining members, said base adapted to receive a magazine or dome supporting collar having latching members formed thereon and adapted to be projected into the base to permit the latching members to be moved into locking engagement with certain of the retaining members when the collar is rotated with respect to the base.

It is an important object of this invention to provide a conical cup dispenser having an improved base member embracing a removable lining band provided with a plurality of teeth or retaining members, with the teeth directed radially inwardly and disposed in substantially parallel planes, with the teeth of the upper or innermost group serving as a stop for a dome or magazine supporting collar having locking members integrally struck therefrom and adapted to be moved into locking engagement with the teeth of the innermost group when the collar is rotated with respect to the base.

Other and further important objects of this invention will be apparent from the disclosures in the specification and the accompanying drawings.

This invention (in a preferred form) is illustrated in the drawings and hereinafter more fully described.

On the drawings:

Figure 1 is a side elevation of a cup dispenser embodying the principles of this invention mounted in position upon a vertical support.

Figure 2 is an enlarged plan view of the dispenser base taken on line II-II of Figure 1.

Figure 3 is a vertical detail section of the base taken on line III-III of Figure 2 showing a plurality of cups in position with one cup partially removed from the base.

Figure 4 is a top plan view of the dispenser base showing a cup in position with the margin of the cup scalloped or deflected to permit passage of a cup through the base.

Figure 5 is an enlarged vertical central section through the lower portion of the dispenser illustrating the position of the locking means for securing the magazine in locked position within the base.

Figure 6 is a transverse section of the dispenser taken on line VI—VI of Figure 5.

Figure 7 is a fragmentary developed plan view of the lining band of the dispenser base.

5 Figure 8 is a vertical sectional view of the supporting members for the dispenser taken on line VIII—VIII of Figure 6.

Figure 9 is a top plan view of a modified form of base for the dispenser.

10 Figure 10 is an enlarged vertical central section of the modified form of base taken on line X—X of Figure 9.

Figure 11 is a top plan view of another spring band type of dispenser base and supporting bracket.

15 Figure 12 is a developed plan view of the spring band type dispenser base illustrated in Figure 11.

As shown on the drawings:

20 The reference numeral 1 indicates a wall or other suitable support having rigidly secured thereon by means of screws or the like a socket or bracket 2 shaped to afford a dove-tailed groove for the reception of a dove-tailed web or bracket 3, the upper portions of the flanges of which are deflected to afford shoulders 3^a. The flanges of the bracket 3 converge or taper slightly to permit the bracket 3 to frictionally fit in the wall bracket 2 with the shoulders 3^a adapted to seat upon the upper edges of the flanges of the supporting bracket 2 as illustrated in Figure 8 to prevent the bracket 3 from wedging too tightly within the wall bracket 2 or from passing therethrough.

25 The dispenser proper comprises a cylindrical cup holding dome or magazine 4 closed at its upper end and constructed of glass or other suitable material. The lower end of the cup container is secured by means of a packing of cement or the like within a metal base ring 5 provided with a circular flange or offset shoulder at 6. The lower portion of the container base ring 5 is adapted to be removably engaged within a cylindrical supporting housing or metal bottom section 7 which forms the lower portion of the dispenser and has the bracket 3 rigidly engaged longitudinally upon the exterior thereof.

30 The lower margin of the container base ring 5 is deflected inwardly to afford a channel-shaped circular flange 8 against which the lower end of the glass cup container 4 is adapted to seat as clearly illustrated in Figure 5. Struck or cut from the channel flange 8 at spaced intervals are a plurality of downwardly projecting latch members or locking hooks 9.

35 The supporting housing 7 has a metal liner band 10 removably engaged therein and seated upon a stop flange 11 which is integrally formed on the lower margin of the supporting housing 7. Integrally cut or formed on one end of the liner band 10 is a dove-tail projection 12 adapted to be removably en-

gaged in a dove-tail recess 13 formed in the opposite end of the liner band when said liner band is bent into a cylindrical form to form a lining for the supporting housing 7. Integrally formed on both the upper edge and 70 the lower edge of the liner band 10 are a plurality of rounded teeth or projections 14 which are equi-distantly spaced around the band and are bent inwardly at substantially right angles to the band to be positioned radially to form a group of upper teeth and a group of lower teeth with the teeth in the lower group positioned directly below the teeth of the upper group. The two groups of teeth are positioned in parallel planes and afford retaining means preventing conical cups 15 from falling downwardly out of the container 4 and through the base housing 7. The upper group of teeth 14 serve as a support for holding a stack of conical cups 15 within the 80 dispenser with the lowermost cup seated in contacting relation with the upper group of teeth 14 and having the apex thereof projecting through the base housing 7 and the liner band 10 out through the bottom of the dispenser to be exposed to conveniently permit the lowermost cup to be first drawn through the upper group of teeth 14 causing the margin of the cups to flex into the spaces between adjacent teeth 14 to temporarily scallop the 85 margin of the cups to ease the withdrawal movement of said cups from the dispenser. The lowermost cup is first drawn downwardly between the upper group of teeth 14 and then passes between the lower group of teeth 90 14 which also serve to cause the drinking margin of the cup to be scalloped or flexed as clearly illustrated in Figure 4. It will thus be noted that the removable liner band 10 contains a primary group of retaining 95 teeth and a lower or secondary group of retaining teeth with the teeth of the secondary group positioned directly below the teeth of the primary or upper group.

100 In case two or more cups are accidentally drawn from the container 4 through the primary or upper group of retaining teeth 14, said cups are adapted to pass into the space afforded between the upper and lower groups of teeth which will cause the lower group of teeth to act as a second retaining means for the extra cups to prevent the same from passing through the liner ring or band so that only the lowermost cup will be withdrawn from the bottom of the dispenser. This arrangement of the double layer of teeth insures dispensing of the cups one at a time.

110 The teeth formed on the margin of the liner band 10 are adapted to be bent at substantially right angles to the band after which 115 the band is rolled into a cylindrical form with the dove-tail 12 engaged in the dove-tail socket or recess 13 to permit the cylindrical liner to be engaged in the upper end of the base housing 7 to seat upon the bottom 120 130

flange 11. The dome or cup container 4 is filled with a stack of nested conical cups 15 and then has the base ring 5 thereof engaged in the upper end of the base housing 7 with the channel groove 8 seated upon the upper 5 group of teeth 14 and with the shoulder 6 of the base ring 5 seated upon the upper edge of the base housing 7 as clearly illustrated in Figure 5. The base ring 5 is inserted into the base housing 7 in a position to permit the latching members 9 to be projected downwardly between the upper teeth 14 after which the base ring 5 and the container 4 are slightly rotated within the base housing 7 thereby permitting the latching members 10 9 to be lockingly engaged beneath certain of the upper teeth 14.

Figures 9 and 10 illustrate a modified form of a dispenser base comprising a cylindrical housing or band 16 constructed of metal and 20 having struck or cut therefrom intermediate the upper and lower edges thereof a plurality of projections or teeth 17 which are deflected inwardly at substantially right angles and are radially disposed in substantially the same plane to form an upper or primary group of cup supporting teeth. Integrally formed on the lower margin of the base housing 16 are a plurality of projections or teeth 25 25 which are deflected inwardly at substantially right angles to the base housing 16 and are radially positioned within the same plane parallel to the plane of the teeth 17 and directly below said teeth. The upper or primary set of teeth 17 are positioned below the upper edge of the cylindrical base housing 16 to permit the base ring 5 of a cup dispenser or dome 4 to be removably engaged within the base housing 16 similar to the arrangement shown in Figure 5 with the lower 30 channel flange 8 of the base ring 5 seated on the teeth 17 with the latching members 9 projecting through the spaces between the teeth to permit the base ring 5 to be rotated 40 within the base housing 16 causing the latching members to lockingly engage beneath certain of the teeth 17 to hold the base ring 5 removably locked within the base housing 45 16.

50 Braised or otherwise rigidly secured longitudinally upon the exterior of the base housing 16 is a supporting bracket 19 having marginal flanges 20 which converge or taper slightly and are offset to form shoulders 21 near their upper ends. The supporting bracket 19 is adapted to be slidably engaged in the upper end of a wall bracket 22 which is also formed with dove-tailed or converging flanges on the upper edges of which the 55 shoulders 21 of the supporting bracket flanges 20 are adapted to seat to hold the base housing supported in position. Conical cups are adapted to be dispensed through the bottom of the base housing 16 similar to the method 60 described in connection with the cup dis-

65 penser illustrated in Figures 1 to 8 inclusive.

70 Figures 11 and 12 illustrate another modified form of dispenser base housing which comprises a metal strip or band 23 having a row of teeth 24 struck therefrom intermediate the upper and lower edges of the band and a lower row of teeth 25 integrally formed in spaced relation on the lower margin of the band 23. The teeth 24 and 25 are deflected to be positioned at substantially right angles to the plane of the band 23 so that the teeth 25 are positioned in alignment with the teeth 24 and parallel thereto. The end margins of the base band 23 are bent outwardly to afford supporting flanges 26 which are offset to afford shoulders 27 near the upper margin of the flanges. The base band 23 is adapted to be rolled or curled into a cylindrical form to form a resilient or spring base section permitting the flanges 26 thereof to be slidably engaged in a dove-tail wall bracket 28 with the shoulders 27 seated upon the upper edges of the flanges of the wall bracket 28 to hold the dispenser base housing 23 in proper position to support a cup container 4 and its base ring 5 similar to the arrangement shown in Figure 1. The base ring 5 may be rotated after being inserted within the base housing 23 to permit the latching members 9 to engage beneath certain of the teeth 24 to lock 90 the container 4 and its base ring 5 within the base housing 23. Conical cups or containers are adapted to be dispensed through the bottom of the base housing 23 downwardly between the upper or primary set of teeth 24 and then through the lower or secondary set of teeth 25 similar to the method described in connection with the operation of the dispenser illustrated in Figures 1 to 8 inclusive.

95 It is of course understood that many changes may be made, and numerous details of construction may be varied through a wide range without departing from the principles of this invention, and that it is not purposed limiting the patent granted thereon, otherwise than necessitated by the scope of the appended claims.

100 I claim as my invention:

105 1. A cup dispenser comprising a container 115 adapted to receive a stack of nested cups, a base ring secured to said container, a supporting housing for removably receiving said base ring, a plurality of groups of radially directed members within said supporting housing with the members of one group positioned directly below the members of another group and arranged parallel thereto, and latching means carried by said base ring adapted to lockingly engage with members of one of said groups to hold the container 120 and said base ring latched within said supporting housing.

125 2. A cup dispenser comprising a container adapted to receive a stack of nested cups, a base ring secured on said container, a toothed

supporting housing adapted to receive said base ring, and latching means carried by said base ring adapted to be removably engaged with certain of the teeth of said supporting housing to hold the container locked with respect to said supporting housing.

3. A cup dispenser comprising a supporting housing having groups of parallel cup supporting and separating members formed therein, a cup container removably engaged in said supporting housing, and latching means carried by said cup container adapted to be moved into locking engagement with certain of said cup supporting members to hold the container locked with respect to said supporting housing.

4. A cup dispenser comprising a supporting housing, groups of teeth within said supporting housing with the teeth of one group disposed in a plane parallel to the teeth of another group and directly beneath said teeth, a cup container, a base ring secured thereon and adapted to fit into the upper end of said supporting housing, and latching members integrally formed on said base ring adapted to be moved downwardly between the teeth in one group and then be moved into locking engagement with certain of the teeth of said group when the base ring is rotated within the supporting housing.

5. A cup dispenser comprising a supporting housing, means for mounting the same upon a support, layers of parallel teeth formed within said supporting housing with the teeth in one layer positioned directly beneath the teeth in another layer, a cup container removably engaged in the supporting housing and seated upon one layer of said teeth, and latching means carried by the container adapted to be moved into locking engagement with certain of the teeth of said layer of teeth to hold the container locked with respect to the supporting housing.

6. A cup dispenser comprising a supporting housing, groups of cup supporting and separating teeth formed in said supporting housing, a cup container removably engaged in said supporting housing, and latching means on said container adapted to be moved into locking engagement with certain of said teeth to hold the container locked with respect to the supporting housing.

7. A conical cup dispenser comprising a supporting housing having layers of cup supporting and separating teeth formed therein, a cup container removably engaged in said supporting housing and resting on one layer of said teeth, and latching means carried by said container adapted to be moved into locking engagement with certain of the teeth of said supporting layer of teeth when the container is partially rotated with respect to said supporting housing.

8. A conical cup dispenser comprising a container adapted to receive a stack of coni-

cal cups, a base ring secured on said container, a supporting housing for removably receiving said base ring, a liner band engaged within said supporting housing, and groups of teeth integrally formed on the upper margin and on the lower margin of said liner band with the teeth in each group directed radially inward to assure dispensing of the cups one at a time.

9. A cup dispenser comprising a container for holding a stack of cups, a supporting housing for said container, groups of projections integrally formed in said supporting housing with the projections of one group disposed in a plane parallel to the plane of the remaining group of projections and positioned directly thereabove, and latching means carried by said container adapted to be moved into locking engagement with projections of one of said groups.

10. A cup dispenser comprising a container for holding a stack of nested cups, a supporting housing for removably receiving said container, parallel layers of projections formed in said supporting housing with one of said layers of projections serving as a seat against which the lower end of the container comes in contact, and latching means carried by the container adapted to be moved into locking engagement with certain of the projections which are contacted by the container to hold the container removably locked with respect to said supporting housing.

11. A cup dispenser comprising a container adapted to carry a stack of conical cups, a base for supporting the same and having a plurality of layers of projections struck therefrom with the projections in one layer disposed directly beneath the projections of an adjacent layer, and means carried by the container adapted to be removably engaged with the projections of one of said layers to hold the container locked with respect to the base.

12. A cup dispenser comprising a container adapted to carry a stack of nested cups, a supporting housing, a dovetailed liner band removably engaged in said supporting housing and having layers of parallel projections integrally formed thereon, with the projections in one layer disposed directly beneath those in another layer, a base ring secured on the lower end of said container, and adapted to fit into the upper end of said supporting base, locking members struck from a flange formed on the lower end of said base ring and adapted to be projected between the projections of one layer of projectors when the container base ring is engaged in the supporting housing, said locking members adapted to be moved into locking engagement with certain of the projections in said layer of projections when the container base ring is partially rotated within the supporting housing, a wall bracket, and a supporting bracket rigidly

secured on the exterior of said supporting housing and having flanges with deflected shoulders formed therein to seat upon the upper flange edges of the wall bracket when the supporting bracket is engaged therein to hold the supporting housing mounted in position to permit cups to be dispensed from the dispenser.

13. A cup dispenser comprising a container adapted to hold a stack of nested cups, a supporting housing therefor having an inwardly directed flange on the lower open end thereof, a toothed liner band engaged in said supporting housing and resting on said flange, and locking means on said container and co-operating locking means on said band detachably locking the container to said supporting housing when it is applied thereto.

14. A cup dispenser comprising a supporting housing, cup supporting and separating projections therein, and a cup container seating in said supporting housing and having means for entering into latching engagement with certain of said projections to removably lock said container to said housing.

15. A cup dispenser comprising a base having supporting and separating teeth therein, a cup container projected into the base to seat thereon and being rotatable with respect thereto, and latching members on said containers removably locked in engagement with certain of the teeth in said base upon rotational movement of said container.

16. A cup dispenser comprising a container for a stack of internested flexible conical cups, a zone of fingers a distance above the dispensing end of said container and projecting into the path of the stack and engaging the lowermost cup a distance below its upper edge whereby to support said stack, said fingers being rigid and unyielding whereby when the lowermost cup is pulled downwardly its conical wall will be deflected inwardly by said fingers and will bulge outwardly into the spaces between said fingers thereby to ease the withdrawal movement of said cup past said fingers and separation thereof from the stack, and a second zone of fingers a distance below said stack supporting zone and in the path of the withdrawn cup for retaining and preventing dispensing, with the withdrawn cup, of any other cup or cups which may have followed the withdrawn cup through said stack supporting zone, the fingers in said second zone being in vertical alinement with the fingers of said stack supporting zone.

In testimony whereof I have hereunto subscribed my name at New York, New York County, New York.

CESARE BARBIERI.
